UNITED STATES PATENT OFFICE.

EDWARD F. HALLOCK, OF BROOKLYN, NEW YORK, ASSIGNOR OF ONE-HALF TO JOSEPH A. MICHEL, OF BROOKLYN, NEW YORK.

SALES PACKAGE.

1,409,544.

Specification of Letters Patent. Patented Mar. 14, 1922.

Application filed December 2, 1919. Serial No. 341,943.

To all whom it may concern:

Be it known that I, EDWARD F. HALLOCK, a citizen of the United States, residing in the borough of Brooklyn, county of Kings, 5 city and State of New York, have invented an Improvement in Sales Packages, of which the following is a specification.

This invention relates to a sales package and more particularly to a sales package 10 adapted to contain grease or oil or a similar substance and is so constructed that in the use of the same the contents are entirely dispensed therefrom. The sales package made in accordance with this invention, for 15 example, is particularly adapted for use as a grease gun. Much difficulty has heretofore been experienced in the use of grease guns as ordinarily constructed because of the inaccessibility of the parts to which the 20 grease is to be applied; for example, gear cases and differentials of motor vehicles, and the fact that in the ordinary form of grease guns a large proportion of the grease is forced by the piston and not from the gun. 25 It will be understood, however, that while my improved sales package is particularly adapted for use as a grease gun, its uses are not so limited.

The object of the invention is to overcome 30 these difficulties and to provide a sales package of relatively inexpensive construction, convenient for use, and which may be fully emptied, one that is not refillable, and which is leakproof. In carrying out the invention, 35 I preferably employ a cylindrical body member of flexible fabric or any other suitable material treated in such a manner as to be impervious to the grease or oil or other contents of the package and fitted at one 40 end with a spout or nozzle member through which the contents of the package may be forced; and provided at the other end, or in a position oppositely disposed to the discharge nozzle, with means for twisting the 45 body member to collapse the same and thereby create a pressure therein which forces the contents of the package from the nozzle to the place to which the contents are to be applied. It will be understood of course 50 as the body of the package is flexible, it may be used in places which are inaccessible to the rigid bodies of ordinary grease guns, and that due to the flexibility of the body of the package the same may be forced into 55 the nozzle to completely discharge the contents of the package. Other advantages of

my improved sales package will be equally obvious.

In the drawing:

Fig. 1 is an elevation showing one form 60 of my improved sales package.

Fig. 2 is an elevation and partial central longitudinal cross section of the same.

Fig. 3 is a view similar to Fig. 2, showing another form of the invention, and 65

Fig. 4 is also a view similar to Fig. 2 showing still another form of the invention.

Referring to the drawing, and particularly to that form of the invention shown in Figs. 1 and 2, the sales package made in 70

accordance with my invention preferably comprises a body member 10 which is cylindrical, as illustrated, and may be made of any suitable flexible fabric, such for example cotton duck, and is so treated as to be 75

impervious to the material which it is to contain. For example, it may be impregnated with bichromated gelatinous matter including a sufficient quantity of glycerine to maintain the pliability or flexibility of 80

the body member, or with a suitable rubber or gum product, or by being subjected to a suitable oxidized oil treatment, depending, as will be apparent, upon the nature of the 85

material which is to be placed in the package. As illustrated in the drawing, this 90

body member is shown as cylindrical, and while this is the preferable form, it may be made in other configurations without departing from the nature and spirit of the 95

invention. In this, as in other forms of the invention, the body member or casing is non-extensible, but is flexible and made impervious to the contents thereof. As illustrated, one end of the cylindrical body mem- 100

ber 10 is suitably made of smaller diameter to fit over and be secured to a suitable spout member. This spout member preferably 105

comprises a nozzle 12 and a flaring end 13 over which latter the reduced end of the 110

body member 11 is fitted and suitably secured to make a tight joint. Internally at 115

the spout member or discharge end the package is provided with a seal 15 which is made of any suitable material and connected to 120

the periphery of the flared end of the spout member or otherwise in any desired manner, it being understood that this seal member is also made impervious to the contents 125

of the package and is constructed in such a 130

way as to be disrupted by the pressure exerted on the contents of the package and 135

conveyed thereto so as to permit the contents of the package to be discharged through the spout member.

- At the opposite end of the body member, 5 the same is preferably reduced in cross section as indicated at 16 and provided with a collapsing ring 17 and then extended again in a flattened section as indicated at 18 which is closed or sealed by suitable strips 10 of metal 19 or other material or otherwise, the parts of which enclose the flattened end 18 of the body member and are connected by rivets 20 or otherwise with the flattened part of the end of the body member intervening 15 so as to make a tight joint at this end of the package. Furthermore, the strips 19 may be fitted with a ring or other grip 21 so as to facilitate the emptying of the package in the use thereof.
- 20 Now as will be apparent, the package, as hereinbefore described, may contain grease or oil or any other similar material, and in the use thereof the spout member or discharge end of the package is held in one 25 hand with the nozzle placed in the receptacle into which the contents of the package are to be discharged and the opposite end of the package twisted by grasping the ring or other part of the opposite end of the package 30 in the other hand and twisting the same, the twisting operation causing the package to gradually collapse from the twisting end, thereby first creating a pressure within the package which is imparted to the contents 35 thereof and transmitted thereby to the spout seal to break or rupture the same, and by the continued twisting of the end of the package the entire contents thereof may be discharged through the spout end, the entire 40 contents being discharged by the possibility of forcing the collapsed body of the package into the flaring end of the spout member.

By reference to Fig. 3, it will be seen 45 that in carrying out the invention, the body member of the package may be made of ordinary untreated flexible or collapsible but non-extensible fabric indicated at 22 and adapted to contain a suitable cartridge for 50 the grease or other material. In this construction, the body member 22 is contracted at one end as indicated at 23 to fit over the flaring end 24 of a spout member, the nozzle of which is indicated at 25. At the opposite 55 end the construction of the body member is similar to that described in connection with the form of the invention shown in Figs. 1 and 2; that is to say, the opposite end is provided with a reduced section of a 60 collapsing ring 26 and with a flattened extremity fitted with suitable strips 27 to make a tight joint and a twisting ring 28. In this body member a cartridge containing the grease or oil is placed, and as shown in 65 Fig. 3, this cartridge 29 is preferably con-

structed to form a part separate from the exterior casing and made of any suitable material so as to be impervious to its contents. The cartridge 29, as illustrated, is preferably closed at one end as indicated at 70 30. The other end of the cartridge is open and is fitted with a cap having a conical portion 31 open centrally. The cap also includes a flange 32 to which the open end of the cartridge is secured and by which, 75 in any suitable manner, the position of the cartridge is determined in the outer casing of the package. The opening in the cap 31 is normally closed by a seal 33, which, in the use of the package, is disrupted in the same 80 manner as hereinbefore described in connection with the seal 15 in the form of the invention shown in Figs. 1 and 2.

Referring to Fig. 4, the invention may assume another form in which the body 85 member comprises an exterior casing in the same manner as that shown in Fig. 3, but in which, as hereinatfer described, the cartridge employed is made an integral part of or lining for the casing. In this structure, 90 as in the other forms of the invention, one end of the casing 34 is of reduced cross section and adapted to fit over and be secured to the flaring member 36 of a suitable spout, the nozzle of which is indicated at 37. Also 95 similar to the other forms of the invention, the other end of the casing and cartridge lining are reduced and fitted with a collapsing ring 38 on the opposite side of which they are extended and flattened and provided 100 with suitable bands 39 to make a tight joint, the bands 39 being provided with a twisting ring 40. The cartridge employed in this form of the invention is indicated at 41 and is made of suitably treated paper or any 105 other material made impervious to the grease, oil or other substance which it is to contain. The closed end of the cartridge is indicated at 42. The opposite open end of the cartridge as indicated at 43 is of reduced cross section and preferably rounded and open at its extremity, the opening being normally closed by a disruptable seal 44 also made of suitable material which is treated in any desired way so as to make the same impervious to the contents of the cartridge. 110 In this construction, the cartridge is made extensible under pressure by being provided with series of longitudinal ribs or corrugations 45 which are normally contracted, but 115 which extend under pressure to increase the diameter of the cartridge in order to prevent the cartridge from breaking or becoming ruptured in discharging the contents thereof by transferring the pressure from the cartridge 120 when the same is extended to the outer casing or body member which then retains the cartridge in position and carrying the pressure prevents the cartridge from being 125 broken.

The forms of the invention as shown in Figs. 3 and 4 are used in precisely the same manner as that described in connection with the form of the invention shown in Figs. 5 1 and 2 and as will be apparent, the nozzle members may be threaded exteriorly at their extremities as indicated at 46 and provided with caps 47 to prevent the leakage of the contents of the package after the seals have 10 been disrupted and the entire contents of the package have not been utilized at one time. It will also be obvious that while I have herein shown and described my improved sales package as adapted for use in containing and dispensing oil or grease and in a cylindrical form, it may be used for other obvious purposes and made in any desired configuration.

I claim as my invention:

20 1. A sales package, comprising a body member of flexible material made impervious to the contents thereof, a discharge member secured to the body member, a collapsing member associated with the body member 25 in a position oppositely disposed to the discharge member, and means also associated with the body member adjacent the collapsing member, to co-operate with the collapsing member for twisting the body member 30 thereby collapsing the same and creating a pressure therein to cause the discharge of the contents of the body member.

2. A sales package, comprising a body member of flexible material made impervious to the contents thereof, a discharge member secured to one end of the body member, a collapsing member associated with the body member adjacent the opposite end thereof, and means attached to the said opposite end of the body member for twisting the same, thereby co-operating with the collapsing member to create a pressure in the body member to force the contents of the same therefrom.

45 3. A sales package, comprising a body member of flexible material made impervious to the contents thereof, a discharge member secured to the body member, a seal within the discharge member, a collapsing ring associated with the body member in a position oppositely disposed to the discharge member, and means attached to the body member and adjacent to said collapsing ring for co-operating therewith in order to twist the body member, thus collapsing the same and creating a pressure therein to disrupt the said seal and permit the discharge of the contents of the body member.

4. A sales package, comprising a body member of flexible material made impervious to the substance to be contained therein, a discharge member secured to one end of the body member, a seal within the discharge member, a collapsing ring associated with the opposite end of the body member, and

devices connected to the said opposite end of the body member for twisting the body member, and co-operating with the said collapsing ring to collapse the body member, thereby creating a pressure therein to disrupt the seal and permit the discharge of the contents of the body member. 70

5. A sales package comprising a body member of flexible material made impervious to the substance to be contained therein, a discharge spout secured to the said body member, a disruptable seal in the said discharge spout, a collapsing ring attached to the said body member, and devices attached to the body member adjacent the collapsing ring by which the body member may be twisted to create a pressure therein to disrupt the seal and permit the discharge of the contents thereof. 75

6. A sales package comprising a cylindrical body member of flexible material made impervious to the substance to be contained therein, a discharge spout connected to one end of the body member, a disruptable seal in the discharge spout, a collapsing ring adjacent the other end of the body member, and means attached to said other end of the body member by which the same may be twisted, beginning at the collapsing ring so as to twist the body member, collapsing the same and creating a pressure therein to disrupt the seal and permit the discharge of the contents thereof. 80 90

7. A sales package comprising a body member of flexible material, a discharge spout secured to the body member, means also secured to the body member in a position oppositely disposed to the discharge spout for twisting the same, a cartridge member within the body member made of material impervious to the contents of the cartridge and provided with ribs or corrugations to be extensible under pressure, and a seal member also made impervious to the contents of the cartridge and adapted to be broken under pressure to permit the discharge of the contents of the cartridge through the said discharge spout. 100 105 110

8. A sales package comprising a cylindrical body member of flexible material, a discharge spout connected to one end of the body member, means at the other end of the body member for twisting the same, a cartridge within the body member made of material impervious to the contents thereof and provided with series of ribs or corrugations to make the same extensible under pressure, and a seal member for normally closing the said cartridge but disruptable under pressure to permit the discharge of the cartridge through the said discharge spout. 115 120 125

Signed by me this 24th day of November, 1919.

EDWARD F. HALLOCK.
